UNITED STATES PATENT OFFICE.

THOMAS NOGIER, OF LYON, FRANCE.

APPARATUS FOR STERILIZING LIQUIDS BY MEANS OF THE ULTRA-VIOLET RAYS.

1,091,382.

Specification of Letters Patent. Patented Mar. 24, 1914.

Application filed May 11, 1911. Serial No. 626,599.

To all whom it may concern:

Be it known that I, THOMAS NOGIER, a citizen of the French Republic, and resident of Lyon, France, have invented certain new and useful Improvements in Apparatuses for Sterilizing Liquids by Means of the Ultra-Violet Rays, of which the following is a specification.

This invention relates to an apparatus for sterilizing running water or other liquids with ultra violet rays.

In the accompanying drawings Figure 1 is a vertical central section of the apparatus. Fig. 2 is a vertical section on the line B—B of Fig. 1. Fig. 3 is a vertical sectional view of a modified form of the apparatus.

The sterilizing apparatus shown in Figs. 1 and 2, comprises a casing made of two parts 36, 37 which are joined together along their longitudinal edges and are secured together by means of bolts or screws which draw the ears 38 together. The part 37 is formed at its center with a tubular extension 39 through which the liquid to be sterilized passes to the apparatus. A duct 40 is formed in the metal wall and communicates with the tubular extension 39, and the upper part of the interior of the envelop. The liquid flows through the envelop and around the quartz lamp 41 and escapes at the opposite lower end through a duct 42 also formed in the metal wall of the envelop. The duct 42 communicates with a central tubular extension 43 which is in alinement with the tubular extension 39. Stuffing boxes 45 fit on the tubular extensions, and to these are connected supply and inlet pipes 44.

Secured to one end of the apparatus is a plate 46 having a central projection 47 over which a socket 48 fits. The socket is provided with a central lug 49, to receive one end of the lamp. A ring 50, provided with claws 51 is mounted on the socket 48, to assist in holding the lamp in position. The lug 49 engages a depression in the end of the lamp 41 and the claws 51 hold the latter laterally in position. At the other end of the envelop or casing is a plate 52 which is similar to plate 46 and is provided at its center with a threaded projection 53. Mounted on the threaded projection is a socket, formed with a center lug 54, and over the socket fits a ring 55 provided with claws 56. The lug 54 engages a depression at one end

of the lamp 41 and the claws 56 fit over the 55 lamp to hold same in position. The socket 54 is adjustable on the threaded projection 53, and is locked in position by means of nuts 57 and 58. A layer of lead is interposed between the lamp lugs 49 and 54 and 60 the depressions in the ends of the lamp to avoid the contact between hard bodies. By screwing the rings 50 and 55 on the sockets the claws 51 and 56 may be adjusted to properly support the lamp. 65

The modified form of apparatus shown in Fig. 3 is more especially intended to produce the sterilization of wine; it might however be applied as well to the sterilization of any other liquid. The lamp 60 is surrounded by 70 a casing 61 which is soldered thereto at 62 and 63. The casing 61 carries two tubular extensions 64 and 65 the one (64) being an inlet for the liquid to be sterilized, while the other extension (65) serves as an outlet for 75 the sterilized liquid. The relation between the diameter 66 of the casing 61 and the diameter 67 of the lamp 60 may vary so as to give the layer of liquid to be sterilized a thickness which is adapted to allow the 80 complete sterilization with the least possible expense of current. The device just described is placed in a tank 68. 69 and 70 indicate electrodes which are connected to the lamp as shown in Fig. 3. 85

Having now fully described my said invention, what I claim and desire to secure by Letters Patent, is:

1. In an apparatus for sterilizing liquids, the combination of a casing, formed with 90 oppositely disposed hollow trunnions which communicate with bores formed in the walls of the casing and which communicate with the interior of the casing at opposite ends thereof, an inlet pipe communicating with 95 one of the hollow trunnions, an outlet pipe communicating with the other hollow trunnion, stuffing boxes between the hollow trunnions and the inlet and outlet pipes, a lamp supported lengthwise of the casing and immersed in the water passing therethrough. 100

2. In an apparatus for sterilizing liquid, the combination of an elongated casing formed in sections, each section having a hollow trunnion which communicates with 105 an inclined bore formed in the section, one of said bores terminating near the top and communicating with the top of the casing,

the other bore terminating near the bottom of and communicating with the casing, inlet and outlet pipes communicating with the hollow trunnions, stuffing boxes between the said pipes and the said trunnions, a lamp supported in the casing and immersed in the liquid passing therethrough.

In testimony whereof I have hereunto set my hand in presence of two witnesses.

THOMAS NOGIER.
